(57) **CLAIM**

The ornamental design for a display panel or screen with animated graphical user interface, as shown and described.

DESCRIPTION

FIG. 1 is a front view of a first image in a sequence of a display panel or screen with animated graphical user interface showing our new design; and,

FIG. 2 is a second image thereof. The appearance of the image transitions sequentially between the images shown in FIGS. 1-2. The process or period in which an image transitions to another forms no part of the claimed design. The broken lines in the figures represent portions of the display panel or screen with animated graphical user interface that form no part of the claimed design.
